Specification for Design.

Patented July 26, 1921.

Application filed November 15, 1920. Serial No. 424,301. Term of patent 14 years.

To all whom it may concern:

Be it known that I, CLARENCE S. PARK, a citizen of the United States, residing at East Butler, in the county of Butler and State of Pennsylvania, have invented a new, original, and ornamental Design for Rubber Tires, of which the following is a specification, reference being had to the accompanying drawing, forming a part thereof.

Figure 1 is a plan view of a segment of a tire showing my design;

Fig. 2 is a transverse section on the line 2—2 of Fig. 1.

I claim:

The ornamental design for a rubber tire, as shown.

In testimony whereof I affix my signature.

CLARENCE S. PARK.
